United States Patent Office

Des. 182,973
Patented June 3, 1958

182,973

SNACK TRAY

Jean O. Reinecke, Oak Park, Ill., assignor to Proven Products, Inc., Evanston, Ill., a corporation of Illinois

Application September 16, 1957, Serial No. 47,746

Term of patent 7 years

(Cl. D44—10)

Fig. 1.

Fig. 2.

Fig. 3.

Fig. 4.

Fig. 5.

Fig. 6.

Fig. 1 is a perspective view of a snack tray embodying my new design;

Fig. 2 is an enlarged top plan view of the tray;

Fig. 3 is a side view thereof;

Fig. 4 is an end view of the tray looking from the left of Fig. 3;

Fig. 5 is a similar view looking from the right of Fig. 3; and

Fig. 6 is a cross-sectional view taken substantially along the line 6-6 of Fig. 2.

I claim:

The ornamental design for a snack tray, substantially as shown.
